UNITED STATES PATENT OFFICE.

WILLIAM SCHEU, OF MAYWOOD, ILLINOIS, ASSIGNOR TO OIL PRODUCTS APPLIANCE CO., OF MAYWOOD, ILLINOIS, A CORPORATION OF ILLINOIS.

MULTIPLE-COMPARTMENT TANK.

Application filed November 5, 1923. Serial No. 672,839.

To all whom it may concern:

Be it known that I, WILLIAM SCHEU, a citizen of the United States, and a resident of Maywood, Cook County, Illinois, have invented certain new and useful Improvements in Multiple-Compartment Tanks, of which the following is declared to be a full, clear, and exact description.

This invention relates to multiple compartment tanks, and its principal object is to provide a leak proof, sheet metal tank, having a plurality of separate compartments for storing liquids, such as oils, gasoline and so forth. Tanks of this character are usually made of sheets of metal, welded together, and where a partition is employed for dividing the tank into two or more compartments, much difficulty is encountered in producing a leak proof tank, having a neat, finished appearance at the joint between the partition and side walls thereof. According to the present invention I make all of the joints between the partition and side walls, at the corners of the tank, by welding the parts together, and this permits any surplus metal at the welded joints to be ground away without weakening the joint. The top and bottom pieces are also welded in place on the side walls and end walls. In accordance with this invention a leak proof multiple compartment tank is produced economically, and in less time and with less labor than is ordinarily required for constructing a multiple compartment tank of equal capacity.

The invention is clearly illustrated in the accompanying drawing in which:—

Fig. 1 is a perspective view of a multiple compartment tank embodying the preferred form of the present invention; Fig. 2 is a perspective view illustrating one of the steps of assembling the parts; Fig. 3 is a vertical, longitudinal section taken on the line 3—3 of Fig. 1; Fig. 4 is a vertical cross section taken on the line 4—4 of Fig. 3; Fig. 5 is a vertical cross section taken on the line 5—5 of Fig. 3; Fig. 6 is a view looking at the bottom of the tank, and Fig. 7 is a plan of a modified form of the invention.

Referring to the said drawing, and first to Figures 1 to 6 inclusive, the reference characters 10, 11 designate the side and end walls, 12 the top, 13 the bottom pieces, and 14 the partition. The tank is preferably rectangular in form, and the partition di-

vides it into two separate compartments, each capable of storing liquids of all kinds.

In the construction illustrated, two sheets of metal are used to make the side and end walls each sheet being bent at 15 to form a corner of the tank. In the finished tank the edges along the ends of the two sheets are welded together at the corners 16. The partition 14 extends across from one side wall to the other, and preferably in an oblique direction, and has end portions 14^a, 14^b that run to the corners 16 of the tank and are welded to the side and end walls thereat. The upper and lower edges of the partition are welded to the top piece 12, and bottom pieces 13. The top 12 comprises a single sheet having down turned flanges 12^a which fit inside the top portions of the side and end walls, and are welded thereto. The top is also welded to the partition. The bottom 70 comprises two bottom portions 13, each having down-turned flanges 13^a welded to the lower edge portions of the side and end walls and to the partition.

In constructing a tank in accordance with the present invention, each side and end wall sheet is bent up to form a right angle bend, the two bent parts of the sheet forming one side and one end wall of the tank. The flanges of the top sheet 12 are bent up, and the corners between the flanges are welded together. The bottom sections are formed up with the flanges 13^a and are made of a size and shape to fit in the spaces at each side of the partition. (See Fig. 6). The 90 partition sheet is notched out at 14^a and bent at two places adjacent the ends, to form the main or oblique part 14^b and the two end portions 14^c. The notches 14^a are made as high as the flange of the top sheet and extend across the end portions 14^c to the oblique portion 14^b.

In assembling and welding the parts together, the top piece 12 is first inverted (see Fig. 2), the partition 14 set upon it, with the notched end portions standing over the side flanges of the top piece, and with the edges of the end portions 14^c flush with the outer faces of the end flanges of the top piece. The partition and top piece are then welded together along the entire line of contact between them. The welding is done by the electric welding process or by an acetylene oxygen welding process as desired. Afterwards the two side and end wall sheets

are placed on the inverted top piece, the end edges being placed along the upright edges of the partition. The side and end wall sheets are thereupon welded to the flanges of the top piece 12 and to the upright edges of the partition, and to each other at the corners 16, in which the upright edges of the partition are located. The flanged bottom sections 13 are then inserted into the tank, and the flanges of said bottom sections are welded to the side and end walls and to the partition, thus completing the tank.

It is to be observed that all of the welding may be conveniently done from the outside of the tank structure as it is being constructed, and that when completed the welded joints may be ground to make a neat finish, without weakening them. The completed tank is enameled, or surface finished in accordance with any of the well known methods, and mounted on a base or on wheels, as is customary. When used for dispensing oils, holes are formed in the top, one over each compartment, and suitable pumps (not shown) are mounted on the top and secured thereto in the usual manner. By running the partition across at places remote from the corners, both openings may be symmetrically disposed on the top.

In the modified form illustrated in Fig. 7, the partition 14* is shown as extending diagonally between opposite corners of the tank. In other respects the construction of this form is similar to the preferred one.

From the above it is evident that any danger of leakage from one compartment to another is eliminated. Moreover, the partition acts as a brace between the walls and increases the stability of the tank.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

1. A multiple compartment tank comprising two similar metal sheets, each having a right angle bend therein to form a side and an end wall, and the two sheets being placed edge to edge to form a rectangle,

tangle, a metal sheet extending transversely between the diagonally opposite meeting edges of said side and end wall sheets, the side and end wall sheets and transverse sheet being welded together at their meeting edges, and top and bottom metal sheets, having marginal flanges extending into the interior of the tank, said top and bottom metal sheets being welded to said side and end wall sheets and to said transverse sheet. 60 65

2. A multiple compartment tank comprising two similar metal sheets, each having a right angle bend therein to form a side and an end wall, and the two sheets being placed edge to edge to form a rectangle, 70 a diagonally extending metal sheet running from side wall to side wall, and terminating at the meeting edges of the side and end wall sheets, the side and end wall sheets and diagonally extending sheet being welded together at their meeting edges, and top and bottom metal sheets welded to said side and end wall sheets and to said diagonally extending sheet. 75

3. A multiple compartment tank comprising two similar metal sheets, each having a right angle bend therein to form a side and an end wall, and the two sheets being placed edge to edge to form a rectangle, a diagonally extending metal sheet having notched 80 end portions running parallel with the side walls, the side and end wall sheets and diagonally extending sheet being welded together at their meeting edges, and flanged top and bottom metal sheets welded to said 85 side and end wall sheets and to said diagonally extending sheet. 90

4. A multiple compartment tank comprising two similar metal sheets, each having a right angle bend therein to form a side and 95 an end wall, and the two sheets being placed edge to edge to form a rectangle, a metal sheet extending transversely between the diagonally opposite meeting edges of said side and end wall sheets, the side and end 100 wall sheets and transverse sheet being welded together at their meeting edges, and a single piece, flanged top wall, welded to the tops of said side and end wall sheets and transverse sheet, and two flanged bottom sections welded to the bottoms of said side and end wall sheets and transverse sheet. 105

WILLIAM SCHEU.
